BICYCLE REFLECTOR

Nicholas A. Amoroso, Hillsdale, N.J., assignor to Bright Star Industries, Inc., Clifton, N.J.

Filed Mar. 27, 1974, Ser. No. 455,133

Term of patent 14 years

Int. Cl. D10—06

U.S. Cl. D10—111

FIG. 1

FIG. 2

FIG. 3

FIG. 4

FIG. 5

FIG. 1 is an isometric view of a bicycle reflector showing my new design;

FIG. 2 is a front view thereof;

FIG. 3 is a side view thereof;

FIG. 4 is a top view thereof; and

FIG. 5 is a bottom view thereof.

The rear of the reflector is flat and unornamented. The cross-hatching which is partially shown for convenience of illustration indicates a reflective surface. It is understood that the cross-hatching is uniformly continuous over the areas on which it appears.

I claim:

The ornamental design for a bicycle reflector, substantially as shown and described.
